INVENTOR:
JOSEPH H. MC EVoy JR.,
BY ATTORNEY.

UNITED STATES PATENT OFFICE.

JOSEPH HENRY McEVoy, JR., OF HOUSTON, TEXAS.

SCREEN PIPE WITH SLOTS DISPOSED IN CIRCULAR AREAS.

Application filed May 19, 1926. Serial No. 110,276.

This invention relates to oil well equipment and it particularly relates to a screen pipe adapted for use in an oil well.

In the production of oil and gas from wells it is common practice to use what is known as an oil string of pipe, this string extending down through the well casing into the oil bearing stratum. It was formerly the practice to drop the oil string in place in the oil bearing stratum and then to perforate it from the inside by means of a perforator, this perforator producing openings in the pipe through which the oil flowed into the interior of the well, the oil being removed from the well either by means of a pump or by natural flow. When the oil string was so perforated the openings produced, whether in the form of round holes or slots, were unsatisfactory inasmuch as they could not be perforated in small sizes, this resulting in the admittance of sand and gravel of considerable size into the well which tended to interfere with the operation thereof. It has, therefore, become standard practice to perforate the lower end of the oil string before putting it in place in the well and it has been found that it is desirable to perforate the oil string with thin elongated slots, these slots acting as a screen and excluding coarse sand and gravel from the well. It has been found, however, that if a sufficient number of openings to freely admit oil is provided the screen pipe, as it is denominated, is considerably weakened, both against longitudinal stresses and against forces tending to twist or collapse it.

I have found that by grouping the slots closer together than in usual practice and confining them into definite areas the capacity of the screen pipe is not reduced, but the strength thereof is considerably increased.

It is accordingly an object of this invention to provide a screen pipe in which the slots therein are grouped together in definite confined areas for the purpose of giving strength to the pipe.

It is readily apparent that the greater the distance between the different groups of slots, the greater will be the strength of the pipe. I have found that by grouping the slots in confined circular areas that greater distance may be provided between the different groups with but a small sacrifice of capacity.

It is accordingly another object of this

invention to provide a screen pipe in which the slots therein are grouped in definite circular areas which are separated by an imperforate continuous bridge which gives the pipe considerable strength. 60

Other objects and especial advantages of this invention will be made evident hereinafter.

Referring to the drawings in which I illustrate this invention:

Fig. 1 is a diagrammatic view illustrating one utility of my invention.

Fig. 2 is a fragmentary plan view showing clearly the manner in which the slots 70 in screen pipe of my invention are located.

Fig. 3 is a section taken on the line 3—3 of Fig. 2.

Fig. 4 is a fragmentary view illustrating 75 the spacing of the slots in an ordinary screen pipe.

In the drawings, 11 represents the floor of a derrick which is situated over a well 12 which is provided with a string of well casing 13 which extends down to a point just 80 above the oil bearing stratum 14. The water string or well casing 13 may be cemented, as shown at 17, to shut out surface water. Extending into the well is a pipe 18 which is commonly termed an oil string. The lower end of the oil string 18 is provided with a screen pipe 19 of my invention which extends through the oil bearing stratum 14, as illustrated in Fig. 1. Extending into the oil string 18 is a pump tubing 21 which extends through a casing head 22 connected to the upper end of the oil string 18 above the derrick floor 11. Near the lower end of the well 12 there is an oil well pump 23 which is connected to the lower end of the pump tubing 21 and by means of which oil is elevated to the surface of the ground. The screen pipe 19 which incorporates the features of my invention is provided with groups of slots 25 which are separated by 90 imperforate bridges 26. 95

The construction of the screen pipe is clearly illustrated in Figs. 2 and 3. The groups of slots 25 include elongated and narrow slots 27 which, as illustrated in Fig. 105 3, may be keystone or wedge-shaped for the purpose of giving relief so that there will be but the remotest tendency for them to clog. The slots 27 of each group 25 (Fig. 2) are of different lengths. These slots 27 are so proportioned that they are situated inside a definite circular area. In other

words, the ends of each of the slots 27 are all in contact with a circle indicated by dotted lines 29 in Fig. 2. By making the slots 27 of each group of slots 25 of different lengths and by confining them in circular areas, a very wide bridge 26 is formed between each group of slots. It should be noted that a much wider bridge is provided by confining the slots in circular areas than would be possible if the slots were grouped in square areas. In Fig. 2 dotted lines 31 represent square areas. It will be seen that the same grouping of slots in square areas would reduce the size of the bridges very greatly and a screen pipe having slots grouped in square areas would be weaker than the screen pipe of my invention having the slots grouped in circular areas. It is, of course, apparent that the capacity of the screen is reduced a little, since certain of the slots of each group must be shorter than the longest slots of the group. It will be seen, however, that but very little of the screen capacity is sacrificed by shortening some of the slots of each group.

In Fig. 4 I illustrate a portion 35 of the screen pipe having elongated slots 36 formed therein according to standard practice. These slots 36, as illustrated, are not confined to definite areas or are not grouped; there are, therefore, no actual bridges provided between the slots. In the ordinary screen pipe, as illustrated in Fig. 4, each slot is spaced a definite distance from the next slot, the slots throughout the entire length of the screen pipe being of substantially the same spacing.

In my invention I group the slots, placing the slots of each group closer together than the slots in an ordinary casing and provide imperforate bridges 26 which are quite large and which give the screen pipe considerable strength. Comparing Fig. 2 with Fig. 4 it will be seen that in the screen pipe of my invention I group seven slots into a comparatively small area as compared with the area occupied by the seven slots in the screen pipe shown in Fig. 4. By placing more slots in a given area, as illustrated by the comparison between Figs. 2 and 4, I am enabled to produce a screen pipe having substantially the same capacity as an ordinary screen pipe, but one which has much more strength because of the imperforate bridges 26.

It is quite important that the screen pipe have considerable strength to withstand any stresses which may be placed thereon. For

example, referring to Fig. 1, the oil bearing stratum 14 is shown in an inclined extension, this being very common in such formations. When the oil bearing stratum is at an inclination there is more or less shifting thereon. If the strainer pipe is not very strong and is unable to resist the stresses imposed thereupon by the shifting formation, it will undoubtedly be collapsed. For this reason it is sometimes practice not to provide the ordinary form of strainer pipes with even as many slots as shown in Fig. 4. It will be quite evident that the screen pipe of my invention will have much greater strength than the ordinary screen pipe because of the grouping of the slots to provide bridges 26 and will, therefore, better resist the stresses imposed thereupon while in a well.

As previously explained the bridges 26 are made larger by grouping the slots in circular areas and this is an important part of the invention. Although my invention has a particular utility in the oil producing industry it should be understood that I may employ the idea in the construction of screens for other uses.

I claim as my invention:

1. A screen pipe having slots formed therein, said slots being parallel and grouped in confined areas so as to provide imperforate reinforcing bridges between each pair of adjacent groups, laterally disposed slots of each group being shorter than slots centrally disposed, to cause each group of slots to fit the boundaries of the area in which it is confined.

2. A screen pipe having slots formed therein, said slots being parallel and grouped in confined areas so as to provide reinforcing bridges between each pair of adjacent groups, laterally disposed slots of each group being shorter than slots centrally disposed, to cause each group of slots to fit the boundaries of the area in which it is confined.

3. A screen pipe having slots formed in the material of the wall thereof, said slots being parallel and grouped in confined areas of a surface of said wall, the length of the slots of each group decreasing progressively from the interior to the exterior of each group.

In testimony whereof, I have hereunto set my hand at Houston, Texas, this 10 day of May, 1926.

JOSEPH HENRY McEVOY, JR.
